UNITED STATES PATENT OFFICE.

LOUIS BALDINGER, OF BROOKLYN, NEW YORK.

DESIGN FOR A COMBINED CLOCK CASE AND ELECTRIC LAMP.

Application filed August 3, 1923. Serial No. 6,939. Term of patent 7 years.

To all whom it may concern:

Be it known that I, LOUIS BALDINGER, a citizen of the United States of America, residing at Brooklyn, county of Kings, and State of New York, have invented a new, original, and ornamental Design for a Combined Clock Case and Electric Lamp, of which the following is a specification, reference being had to the accompanying drawing, forming part thereof.

The figure is a perspective elevation of the combined clock case and electric lamp.

I claim:—

The ornamental design for a combined clock case and electric lamp as shown.

LOUIS BALDINGER.
